WILLIAM R. MANLEY, OF NEW YORK, N. Y.

Letters Patent No. 78,301, dated May 26, 1868.

IMPROVEMENT IN PADDLE-WHEELS.

The Schedule referred to in these Letters Patent and making part of the same.

TO ALL WHOM IT MAY CONCERN:

Be it known that I, WILLIAM R. MANLEY, of the city, county, and State of New York, have invented certain new and useful Improvements in Paddle-Wheels for water-craft, and that the following is a full, clear, and exact description and specification of the same.

My invention relates to those paddle-wheels in which the inclination of the paddle to the radius of the wheel is varied during revolution.

The object of my invention is to retain the advantages incident to securing the journal or bearing of the controlling-frame to the guard of the paddle-wheel, and at the same time to prevent the fluctuations in the position of the guard (relatively to the paddle-wheel) from straining the controlling-frame, its connections, and the paddle-wheel.

To this end, the first part of my invention consists of the combination of the controlling-frame of the paddles with the paddle-wheel guard, (or other support for the journal upon which the controlling-frame turns,) by means of a connection between the main wheel and the controlling-frame, which, at all times when the wheel is in action, permits the bearing of the controlling-frame to change its position in relation to the guard-beam whenever the guard-beam changes its position in relation to the main wheel.

My invention consists, further, of the arrangement of the said connection diagonally to the vertical and horizontal directions in which the paddle-wheel guard is moved by strains, whereby the journal or bearing of the controlling-frame is moved to the least extent by equal movements of the paddle-guard in vertical and horizontal directions.

My invention consists, further, in so arranging the paddle-cranks (by which the controlling-frame is connected with the paddles) and the said connection, that the weight of the controlling-frame is divided equally, or thereabouts, between the paddle-wheel and the paddle-wheel guard.

My invention consists, further, of the combination of the controlling-frame, paddle-wheel guard, and said connection, (which constitute the first part of my invention,) with the wheel-shaft, by means of a link connecting the bearing of the controlling-frame and the end of the wheel-shaft, whereby the shafts on which the paddles turn are relieved of the weight of the controlling-frame.

I have deemed it expedient to represent my improvements as applied to a wheel of the Buchanan variety, the simplicity of which renders it easy for me to convey to others a clear understanding of the nature and operation of my invention; and I will proceed to describe the improved wheel, referring to the accompanying drawings, and to the letters of reference marked thereon. In the said drawing—

Figure 1 represents a side view of the improved wheel and a fragment of the guard-beam.

Figure 2 represents a vertical section of the same at the axis of the wheel-shaft; and

Figure 3 is a diagram representing the central lines of some of the members of the paddle-wheel.

The paddle-wheel proper has two frames, A A', supported by and secured to the wheel-shaft B. It has also, in the present instance, eight paddles, C, which are secured to shafts e, which turn in bearings sustained by the paddle-wheel frames A A', so that the inclination of the paddles to the radii of the paddle-wheel may be varied by turning or by rocking the said paddles in the wheel-frames upon the axes of their shafts. Each paddle-shaft is fitted with a crank-arm, D, by which the paddle is controlled, and the series of crank-arms is connected by its crank-pins with the controlling-frame E, which is constructed to turn upon a journal, a, that is eccentric to the paddle-wheel shaft B.

In order that my invention may be embodied in this paddle-wheel, the journal or bearing a of the controlling or eccentric-frame E, although supported at the outer side of the wheel by the guard-beam F, is not rigidly connected with this beam, but is connected with it by an arm, G, having a journal, H, which is fitted to turn in a pillow-block, I, secured to the guard-beam F. As the arm G is free to vibrate upon the axis of its journal H on the guard-beam, while the eccentric-frame E is free to turn upon the journal a at the outer end of the arm, the said arm G, with its journals, constitutes a connection between the said eccentric or controlling-frame and

the guard-beam, and which at all times permits the latter to change its position relatively to the former, or vice versa.

In order that the second part of my invention may be embodied in the said wheel, the arm G is made of such length, and so set upon the guard-beam, that the line connecting the axes of the two journals, H a, (which line is represented in the drawing by the dotted line H a, and is the radial line of the said connection,) is at an angle of forty-five degrees with the horizontal and vertical lines drawn through the axis of the journal H on the paddle-wheel guard, and is therefore diagonal to the vertical and horizontal directions in which the paddle-wheel guard may be moved by strains.

Moreover, (in order that the third part of my invention may be embodied,) the crank-arms D of the paddles are so arranged relatively to the connection formed by the arm G, that the central lines of said crank-arms (indicated by the dotted lines e r) are at the same inclination to the vertical line J J, drawn through the axis of the journal a, that the radial line H a of the said connection is. Hence, when the arm G and the crank-arms of the paddles are of equal length, and the radial line of the said connection is at an angle of forty-five degrees with the vertical line J J representing the direction of the force of gravity, as is the case in the present wheel, the weight of the eccentric controlling-frame E is divided equally between the paddle-wheel and the paddle-wheel guard, and the weight is supported as upon the apex of a right-angled isosceles triangle.

As the strain upon the paddle-shafts, due to this portion of the weight, may be deemed objectionable, I have connected the extension of the journal a of the eccentric-frame directly with a journal, s, formed upon the outboard-end of the wheel-shaft B, by means of a link, N, (represented in dotted lines in fig. 1,) whose ends are fitted to turn upon the said two journals, so that the portion of the weight of the eccentric controlling-frame borne by the wheel-shaft is transmitted directly to it by the link N. When this link is used, there should be a little play in the bearings of the pins of the crank-arms D in the eccentric controlling-frame.

In place of arranging the arm G to sustain the strain as a strut or brace, it may be arranged to sustain it by tension. In this case the journal on the paddle-wheel guard-beam must be arranged above the level of the axis of the wheel-shaft, as, for example, with the axis of the journal at the point g, fig. 3; and this arrangement is advantageous in a sea-steamer, because it permits the paddle-wheel guard to be raised correspondingly, so that it is further above the level of the water. Or, if the second part of my invention is not to be used, the arm G of the said connection may be set vertically upon the paddle-guard, and the paddle-crank arms D set so as to project horizontally from the paddle-shafts e.

Although I greatly prefer to distribute the weight of the eccentric-frame or controlling-frame equally between the wheel-shaft and the guard-beam, this is not essential to the first and fourth parts of my invention, because by varying the angle which the radial line of the said connection forms with the horizontal line passing through the axis of the journal on the guard-beam, and also varying the inclination of the paddle-crank arms, any desired distribution of the weight may be obtained. Thus, for example, if the arm G be so set when first adjusted that its radial line is horizontal, while the radial lines of the paddle-crank arms are vertical, all the weight of the controlling-frame will be thrown upon the paddle-wheel; and if, on the other hand, the radial line of the arm G be vertical, while the radial lines of the paddle-crank arms are horizontal, all the weight will be thrown upon the guard-beam; and by inclining the radial line of the connecting-arm G more or less to a vertical line, and setting the radial lines of the paddle-crank arms conversely, more or less of the weight of the controlling-frame will be thrown upon the paddle-wheel, and correspondingly less or more of it upon the paddle-guard.

The employment of this connection between the paddle-beam and the controlling-frame imparts an elasticity to the whole system of the paddle-wheel which has heretofore been wanting, and not only diminishes the friction of all the journals, but tends greatly to reduce the risk of breakage from the straining of the paddle-guard in a sea-way, if it does not entirely prevent it. This is evident from a consideration of what would take place if the guard-beam were strained. Suppose, for example, it were raised, relatively to the side of the vessel, so as to raise the axis of the journal H to the point h, fig. 3. As the journal can turn in the pillow-block on the guard-beam, the central lines of the connecting-arm G, rod or arm of the controlling-frame, and paddle-crank arms, would assume the mean positions represented by the dotted lines h a', a' r', r' e, fig. 3, in which no one of the parts would be strained out of its natural position, and consequently they would not be unduly strained. The accommodating qualities of the controlling system, therefore, permits all the members of the wheel to accommodate themselves to the varying circumstances which may occur in practice.

In the paddle-wheel represented in the drawings, the angle formed by the radial line H a of the arm G, and the radial lines e r of the paddle-crank arms, is an angle of ninety degrees. Although I believe this to be the best angle for the members, all things considered, for sea-going vessels, when great strength and stability of all parts of wheel are required, I would not confine myself to this angle in cases of wheels for vessels to navigate still waters, where the relative movement of the paddle-wheel guard and vessel is small, and the use of the second part of the invention is not very important, but would in such cases, when the equal distribution of the weight of the controlling-frame was made between the paddle-wheel and the guard-beam, use a lesser angle, say of forty-five degrees, in this way lessening the divergence of the two lines of pressure.

What I claim as my improvement in paddle-wheels having paddles capable, while in action, of varying their inclinations to the radial arms of the paddle-wheel frames, is—

1. The combination of the controlling-frame E of the paddles with the guard-beam F and crank-arm G, substantially as hereinbefore set forth.
2. The arrangement of the crank-arm G diagonally to vertical and horizontal directions in which the guard-beam may be moved by strains upon the vessel, substantially as hereinbefore set forth.

3. The arrangement of the paddle-crank arms D and the crank-arm G at equal angles to a vertical line, substantially as hereinbefore set forth.

4. The combination of the controlling-frame E, guard-beam F, crank-arm G, link N, and main shaft B, substantially as hereinbefore set forth.

In testimony whereof, I have hereto set my hand, this twentieth day of April, 1867.

W. R. MANLEY.
